CLAIM

The ornamental design for a brush assembly, as shown and described.

DESCRIPTION

FIG. 1 shows a front elevation view of a brush assembly showing my new design;

FIG. 2 shows a rear elevation view thereof;

FIG. 3 shows a right-side elevation view thereof;

FIG. 4 shows a left-side elevation view thereof;

FIG. 5 shows a top view thereof;

FIG. 6 shows a bottom view thereof;

FIG. 7 shows a front, bottom, and left perspective view thereof; and,

FIG. 8 shows a back, bottom, and left perspective view thereof.

The broken lines in the drawings illustrate portions of the brush assembly that form no part of the claimed design.

1 Claim, 7 Drawing Sheets
